Primary Examiner — Cynthia R Underwood*(74) Attorney, Agent, or Firm* — RatnerPrestia(57) **CLAIM**

The ornamental design for a computer for reserving a conference room, as shown and described.

DESCRIPTION

FIG. 1 is a perspective view of a computer for reserving a conference room showing our new design;

FIG. 2 is a front view thereof;

FIG. 3 is a rear view thereof;

FIG. 4 is a left side view thereof, the right side view is the same as the left side view;

FIG. 5 is a top plan view thereof; and,

FIG. 6 is a bottom plan view thereof.

The broken lines in the drawings are for the purpose of illustrating unclaimed portions of the computer for reserving a conference room and form no part of the claimed design.

1 Claim, 5 Drawing Sheets(56)
